UNITED STATES PATENT OFFICE.

GILBERT A. RANDALL, OF PHILADELPHIA, PENNSYLVANIA.

SENSITIZED-PAPER HOLDER.

No. 877,454.

Specification of Letters Patent.

Patented Jan. 21, 1908.

Application filed July 19, 1907. Serial No. 384,569.

To all whom it may concern:

Be it known that I, GILBERT A. RANDALL, a citizen of the United States, residing at the city of Philadelphia, in the county of Philadelphia and State of Pennsylvania, have invented certain new and useful Improvements in Sensitized-Paper Holders, of which the following is a specification.

My invention has relation to a holder for containing more particularly in roll form blue print or sensitized paper for keeping the light therefrom and at the same time arranged so as to permit of ready withdrawal of paper from the roll in lengths, as required, without affecting or rendering unfit for use that held still in the holder.

To that end my invention consists, of a holder of the character hereinafter described and claimed.

20 The nature and characteristic features of my invention will be more fully understood from the following description taken in connection with the accompanying drawings forming part hereof, in which.

25 Figure 1, is a front elevational view of a holder embodying therein features of my present invention. Fig. 2, is a view, illustrating partly in horizontal section and partly in elevation the holder and means for supporting in operative position and for holding under tension a roll of blue print or sensitized paper therein. Fig. 3 is a transverse sectional view of the holder enlarged, on the line x, x , of Fig. 1, illustrating a movable flap carrying a cutter for severing the end of paper drawn from the holder and for protecting that portion against the influence of light projecting beyond the outlet opening of the holder. Fig. 4, is an end elevational

40 view of a portion of the holder enlarged, showing the movable flap for permitting the inserting of the roll of sensitized or blue print paper into the holder. Fig. 5, is a similar view, showing a movable flap carrying the

45 cutter occupying a closed or operative portion. Fig. 6, is a sectional view on the line y, y , of Fig. 1, showing the internal inclined table supporting the end of the paper drawn from the roll and guiding it towards an outlet opening in the front wall of the holder, the cutter carrying flap occupying an open or inoperative position to free the outlet opening and an additional opening arranged to permit the drawing of the end of the paper from the holder.

Referring to the drawings 7, is the holder

of my invention, consisting of an oblong receptacle provided with one side or flap 8, hinged at 9, to the base 10, and secured preferably by hooks 12, to the cover or upper wall 11, of the holder 7, to which the hooks are connected and engaging eyes 35 secured to the flap 8. The side wall 13, is suitably connected with the base 10, and upper wall 11, and is provided near the lower end with a transverse opening 14, and with an opening 29, which are normally closed by means of a flap 15, hinged to the base 10, at the point 30, and held in upright or operative position by hooks 31, secured to the end walls of the holder 7, and engaging eyes 32, secured to the flap 15, as clearly illustrated in Fig. 5. The flap 15, at its upper free end and slightly projecting therefrom is provided with a knife blade 16, for a purpose to be presently more fully described. To the side wall 13, by means of brackets 20 and 21, are movably secured U-shaped frames 18 and 19, supporting an oblong curved bar 17. This bar by means of springs 22 and 23, coiled around these frames 18 and 19, is held in yielding engagement with a roll of blue print or sensitized paper 24, mounted on a shaft or rod 25, movably supported by U-shaped bearings or brackets 26 and 27, secured to the end walls 80 of the holder 7. 28, is an inclined table located beneath the roll 24, and terminating below the transverse outlet opening 14, which supports the paper drawn from the roll 24, and guides the same into the outlet 90 opening 14, after which the paper is guided upwards and held against the wall 13 by the flap 15, with its knife blade 16, when the same as shown, for example in Fig. 3, occupies an operative position.

95 The holder is so arranged as that the roll of sensitized paper as well as the end projecting therefrom is wholly protected from the influence of light, at all times. The bar 17, by being held in engagement with the roll 100 24, under the tension of the springs 22 and 23, engaging the frames 18 and 19, carrying the said bar, prevents the unwinding of the paper, except by pulling the same outwards by hand. For this purpose, the flap 15, is 105 first lowered after which the end of the paper 24, thus freed from the wall 13, is engaged by the hand of the operator, which is aided in the engagement of the paper by the opening 29, arranged in the lower end of the wall 110 13. The paper is now withdrawn from the holder 7, for the length required, after which

the flap 15, is raised and by the hooks 30, is again held flat against the wall 13. The paper by moving the same in a downward direction will be cut or severed by the projecting cutting edge of the knife 16. Any waste of paper by the straight cutting of the same is thus effectually prevented. At the same time that portion of the paper, which projects beyond the outlet opening 14, of the holder 7, is protected against the action of the light by the flap 15, with its knife, by holding it in close engagement with the wall 13, thereof. An opening 34, arranged in the table 28, opposite the opening 29, in the wall 13, aids in the introduction of the paper into the outlet opening 14, after a fresh roll of sensitized paper has been placed in the holder 7, by the opening of the flap 8, thereof.

Having thus described the nature and object of my invention what I claim as new and desire to secure by Letters Patent is:—

1. A holder of the character described, comprising an oblong hinged receptacle arranged to be parted, a rod removably mounted in the receptacle for containing a roll of paper, means for holding the roll of paper

under spring tension, said receptacle provided with a transverse slot in one wall near the bottom and a hinged flap for closing the opening of the holder and protecting an end 30 of paper of the roll exposed beyond the receptacle from the effect of light upon the same.

2. A holder of the character described, comprising an oblong hinged receptacle arranged to be parted, a rod arranged for carrying a roll of paper and supported under spring tension therein, an inclined table located below the roll and an opening extending transversely of one wall of the receptacle and a hinged knife edged flap for closing the opening and protecting an exposed end of paper of the roll beyond the receptacle from the effect of light upon the same.

In witness whereof, I have hereunto set my signature in the presence of two subscribing witnesses.

GILBERT A. RANDALL.
